[57] CLAIM

The ornamental design for a wheel, as shown.

DESCRIPTION

FIG. 1 is a perspective view of the wheel of our new design from the front;

FIG. 2 is a front elevation view thereof to an enlarged scale;

FIG. 3 is a rear elevation view thereof to an enlarged scale; and

FIG. 4 is a side elevation view thereof, the wheel having substantially the same appearance in side elevation about the circumference thereof.

FIG. 1

FIG. 4

FIG. 2

FIG. 3
